(57) **CLAIM**

The ornamental design for an auger flight stabilizer gusset, as shown.

DESCRIPTION

FIG. 1 is a side view of the auger flight stabilizer gusset; FIG. 2 is a top view of the auger flight stabilizer gusset; FIG. 3 is an end view of the auger flight stabilizer gusset; FIG. 4 is a perspective side view of the auger flight stabilizer gusset showing it combined with an exemplary auger; and, FIG. 5 is a side view of the auger flight stabilizer gusset showing it combined with an exemplary auger. The broken line showing of an auger is included for the purpose of illustrating environmental use only and forms no part of the claimed design.
